(57) **CLAIM**

The ornamental design for a spacer as shown and described.

DESCRIPTION

FIG. 1. is a perspective view of a four-lobed spacer showing the design;

FIG. 2. is a second perspective view thereof;

FIG. 3. is a front elevation view thereof;

FIG. 4. is a rear elevation view thereof;

FIG. 5. is a left side elevation view thereof;

FIG. 6. is a right side elevation view thereof;

FIG. 7. is a top plan view thereof;

FIG. 8. is a bottom plan view thereof;

FIG. 9. is a perspective view of a three-lobed spacer showing the design;

FIG. 10. is a second perspective view of the three-lobed spacer showing the design;

FIG. 11. is a front elevation view of the three-lobed spacer showing the design;

FIG. 12. is a rear elevation view of the three-lobed spacer showing the design;

FIG. 13. is a left side elevation view of the three-lobed spacer showing the design;

FIG. 14. is a right side elevation view of the three-lobed spacer showing the design;

FIG. 15. is a top plan view of the three-lobed spacer showing the design; and,

FIG. 16. is a bottom plan view of the three-lobed spacer showing the design.

Broken or dotted lines show surface shading or structural features of the spacers, and do not represent elements of the claimed design.
